METHOD AND MEANS FOR TEMPORARILY
PLUGGING CONDENSER LEAKS

Oscar J. Wheeler, Jersey City, N. J.

Application March 1, 1933, Serial No. 659,109

5 Claims. (Cl. 137—99)

My present invention relates generally to water-tube condensers, and has particular reference to a method and means for temporarily plugging leaks.

The leakage of cooling water from the circulating system of a water-tube condenser into the condensing chamber or space surrounding the tube is a matter of no inconsiderable importance when it is borne in mind that the condensate is usually returned to the boilers, and that any impairment of the purity or quality of the condensate will necessarily have a corresponding effect upon the tubes of the boilers. It is of special importance to guard against such leakage in the case of condensers of the character which are used on many ocean steamers, in which the cooling water is drawn from the sea, inasmuch as the salts which would pollute the condensate are of great potential danger if they are permitted, for any extensive period, to form incrustations upon the interior of the boiler tubes.

It is, however, no simple matter to make permanent repairs in condenser tubes. The procedure is time consuming, relatively expensive, and obviously requires a shutdown of the condenser during the period of its dismantlement and repair.

While those conversant with the art are fully aware of the necessity for promptly remedying leaks, it is not always feasible or convenient to withdraw a condenser from active service the moment that the leakage is discovered to have developed to a point requiring permanent repair. Especially is this the case with ocean liners which usually operate under rigid schedules. Any complete shutdown of the power plant of an ocean steamer, in the midst of a trip, is regularly sought to be scrupulously avoided if it is at all possible for the ship to continue on its journey without actual danger to its cargo or passengers.

It is a general object of my present invention to provide an improved and simplified method and device for temporarily plugging condenser-tube leaks without the necessity for completely shutting down the condenser or withdrawing it from service. By the term "temporary" I refer to a repair which is adequate for at least a few days, and sometimes for as much as a week or two, to maintain the condensate purity above a predetermined safe minimum. By means of my present invention, the cost of expensive cleaning or repairing of boilers, due to the presence of more than a permissible amount of impurities in the condensate, is avoided, without interfering in the least with the continued operation of a

condenser for at least a reasonably sufficient time to permit a planned schedule of operation to be maintained.

The type of temporary repair which my present invention provides for is a purely mechanical one, and consists in effectively plugging relatively minor leaks with a comminuted solid material. Although the type of leak-plugging material which I prefer to employ, and in connection with which my present apparatus and method function with greatest efficiency, is a special composition of a various number of particular ingredients, it will be understood that my present invention does not relate to any particular composition of matter, as such, nor is the present apparatus or method dependent upon the use of any particular leak-plugging material. Merely for the purpose of explaining the general nature of my present invention, I will state that a comminuted fibrous material having the general characteristics of ordinary sawdust is the general type which my present invention aims to employ for the purposes hereinbefore mentioned.

I have found that a comminuted solid material of proper characteristics, if it can be caused to reach the point or area of leakage, will automatically proceed to accumulate itself into gobs or masses which will temporarily plug minor leaks by the ordinary mechanical process of clogging. It is, therefore, a particular feature of my invention to provide a method and device which may be employed economically and simply, and with reliability, to deliver such material to the areas at which it is required, and in a manner whereby the passage of the material through other portions of the circulating system, not requiring repair, will not impair or clog the system or interfere with the smooth continuous operation of the condenser.

Experimentation has shown that the comminuted leak-plugging material is properly effective at the points required, and properly ineffective at other points or areas, only if it is caused to be thoroughly and adequately dispersed or suspended in the water of a circulating system. It is, therefore, a further feature of my invention to provide a means for effecting such dispersion.

Briefly, my invention resides in the step or steps of forming a stream of a high velocity fluid, such as steam, in feeding the solid leak-plugging material laterally into the stream so as to cause a thorough dispersion or suspension; and then injecting the suspension, at high velocity, into the circulating system of the condenser which

is to be temporarily repaired. The injection is caused to be made at the inlet end of the circulating system, and preferably between the pump and the condenser.

5 Other general features of my invention lie in providing a device which is extremely simple in structural nature, feasible and economical to manufacture, install, and use, reliable, and staunch. My present invention provides for a 10 device which is readily attachable to power plant installations already in operation, and is therefore of commercial and practical importance and value.

15 I achieve the foregoing objects, and such other objects as may hereinafter appear or be pointed out, in the manner illustratively exemplified in the accompanying drawing, wherein—

20 Figure 1 is an elevational view of my present device associated with a water-tube condenser, the latter being shown only in general contour; and

25 Figure 2 is a fragmentary cross-section, upon an enlarged scale, of certain portions of the present device.

30 For the purpose of illustrating the general nature of my invention, I have shown a water-tube condenser 10, provided with an inlet 28 for the steam which is to be condensed, and an outlet 12 from which the condensate is withdrawn. The detailed structure of the condenser has not been illustrated, since it is not material to my present invention, but it will be understood that a multiplicity of substantially horizontal tubes are arranged within the body 10, with sufficient 35 space around them to permit the steam flowing into the condenser through the inlet 28 to come into contact with the surfaces of the tubes, thereby causing it to condense. The particular arrangement of the condenser tubes is not of material importance, but it will be understood that the tubes are usually supported at their opposite ends in tube sheets which communicate with the opposite headers 13 and 14. The header 13, for example, may be provided with a baffle which will 40 cause the circulating water to flow toward the other header through a predetermined number of tubes, and to flow back through a predetermined other bundle or number of tubes.

45 The circulating system has an inlet conduit 50 of the character shown at 15, and a suitable pump 16 draws the circulating water from a source of supply and pumps it through the inlet conduit 15 into the body of the condenser. Thence, the circulating water flows through the tubes and is ultimately discharged at the outlet 11.

55 It is obvious that the maintenance of a predetermined degree of purity of the condensate flowing from the outlet 12 requires that the condenser tubes be leak-proof, otherwise more and more of 60 the circulating water would find its way into the condensing chamber and into the condensate. It is inevitable, however, that leakage will develop, in the course of time, and it is therefore customary to test the condensate from time to time 65 to ascertain and maintain a check upon its purity. Sometimes the condensate is caused to pass through a device which automatically and continuously detects impurities, for example, by electrical means, as a result of which it is possible to 70 maintain a constant check upon the condition of the condensate.

75 Regardless of the manner in which the condensate is tested, my present invention provides for a convenient, economical, and reliable method and means for temporarily plugging minor leaks

whenever the purity of the condensate is found to fall below a predetermined minimum. A device of the present character is shown in association with the condenser 10, at the left, and the construction of certain portions of the device is 5 shown more clearly in Figure 2.

The device consists of a chamber or enclosure 17 in which two spaced and aligned nozzles 18 and 19 are arranged. These nozzles are of more or less conventional character, adapted to permit the 10 flow of a fluid therethrough, and designed to transform the energy of the fluid from a pressure condition to one of velocity.

15 Adjacent to the smaller end of the first nozzle 18 is an inlet 20 for the fluid which is used, usually and preferably steam at a pressure of about 175 pounds per square inch. A valve 21, controlled by the handle 22, is adapted to control the inlet opening of the nozzle 18; and when this valve is seated, as shown in Figure 2, there is no 20 flow of fluid through the chamber 17.

25 Communicating with the space between the nozzles 18 and 19 is a pipe or conduit 23 which leads upwardly to a hopper 24 adapted to accommodate a supply of the solid material. In the 25 conduit 23 I arrange a suitable valve or closure 29 whose opening and closing is conveniently controlled by a handle of the character illustratively shown at 25. An ordinary gate valve arrangement is usually satisfactory.

30 Adjacent to the outlet end of the nozzle 19 I provide a valve 26, and this valve communicates through the pipe 27 with the inlet conduit 15 of the circulating system of the condenser. The valve 26 preferably forms a part of the present 35 device, when the latter is manufactured and assembled, and it is provided with threads at its outlet end to enable the same to be readily connected and attached to the inlet conduit 15, as, for example, by means of a nipple or conduit 27 40 of the character shown.

45 When the present device is installed in association with a condenser, it is a relatively simple matter to connect the pipe 20 with a source of high pressure fluid such as steam, and to connect the outlet end of the device to the circulating water system of the condenser, as, for example, by establishing a connection with the inlet conduit 15, in the manner shown. Under normal running conditions, the valves 21, 26, and 29 are closed. A 50 supply of the comminuted, solid, leak-plugging material may be kept in the hopper 24, if desired, to be used when needed, or it may be inserted into the hopper just prior to the time that it is to be used.

55 When it is determined that leakage within the condenser is to be temporarily plugged, it is not necessary to withdraw the condenser from operation nor to interfere in any way with the continued operation of the circulating system. It is 60 merely necessary to open the valve 26, then to open the valve 21, and finally to manipulate the valve 29 to the desired extent. The opening of the valve 22 produces a flow of the steam through the chamber 17, in the form of a stream which 65 flows successively through the nozzles 18 and 19 and thence into the conduit 15. The nozzles cause the stream to develop a high velocity.

70 When the handle 25 is manipulated, a selected quantity of the material is permitted to feed 70 downwardly from the hopper 24 into the space between the nozzles 18 and 19. The material thus encounters the stream of steam in a lateral direction, and an immediate and thorough dispersion 75 of the solid particles results. This suspension 75

then proceeds at high velocity into the inlet conduit 15, and the circulating pump 16 serves to force the suspension, along with the circulating water, into and through the condenser tubes.

5 After the desired quantity of solid material has been fed into the chamber 17, and thus into the circulating system, the valve 29 is shut, and the valves 21 and 26 are then successively closed. The exact amount of material will vary under 10 differing requirements, but experimentation will easily teach the approximate amount of solid material to be used for any given case.

The fact that the solid, leak-plugging material is in finely divided and suspended condition results in an assured circulation of it through the 15 entire circulating system. At the leaky points or areas a certain amount of the circulating fluid will tend to flow out into the condensing chamber, and the suspended particles of leak-plugging 20 material will accumulate in a very short time and mechanically plug the leak. The excess particles, not gathered in this way into plugging relationship with other particles, will continue to pass freely through the circulating system without the 25 slightest impairment of the latter.

Merely by way of example, I will state that the amount of solid material usually employed is about a handful or so; that it takes but a few seconds for this amount to be fed into the injecting device; and that within five or ten minutes, at the most, after the material has been forced 30 into the circulating system in suspended condition, a test of the condensate will usually show that the undesirable leakage has been temporarily remedied. Ordinarily, this temporary relief will be adequate to prevent further leakage for about a week or so; and in the meantime, the condenser may be caused to continue its functioning.

40 It will be understood that changes in the details herein described and illustrated for the purpose of explaining the nature of my invention may be made by those skilled in the art without departing from the spirit and scope of the invention as expressed in the appended claims. It is therefore intended that these details be interpreted as illustrative, and not in a limiting sense.

Having thus described my invention, and illustrated its use, what I claim as new and desire to 50 secure by Letters Patent—

1. The combination with a water-tube condenser including an inlet conduit for the cooling water, of means for injecting a stream of fluid into said inlet conduit at high velocity, and means for dispersing in said stream a predetermined quantity of comminuted leak-plugging solid material. 5

2. The combination with a water-tube condenser including an inlet conduit for the cooling water, of means for injecting a stream of fluid 10 into said inlet conduit at high velocity, and means for dispersing in said stream a predetermined quantity of comminuted leak-plugging solid material, said last-named means comprising a chamber through which said stream flows, a 15 hopper for containing a supply of the solid material, and means for feeding a selected quantity of said material from the hopper into said chamber.

3. The combination with a water-tube condenser including an inlet conduit for the cooling 20 water, of an injector for directing a jet of steam, at high velocity, into said inlet conduit, and means for dispersing in said steam jet a predetermined quantity of comminuted leak-plugging 25 solid material.

4. The combination with a water-tube condenser including an inlet conduit for the cooling water, of an injector for directing a jet of steam, at high velocity, into said inlet conduit, said injector comprising a pair of aligned spaced nozzles, 30 and means for dispersing in said steam jet a predetermined quantity of comminuted leak-plugging solid material, said means comprising a hopper for said material arranged over the space 35 between said nozzles, and means for feeding a selected quantity of said material from the hopper into said space.

5. The herein-described method of temporarily plugging leaks in a water-tube condenser without shutdown, which consists in producing a flow 40 of steam at high velocity through an enclosure, feeding a selected quantity of comminuted leak-plugging solid material laterally into said stream to cause a dispersion of said material in said 45 stream, and injecting said suspension at high velocity into the inlet end of the water-circulating system of said condenser.

OSCAR J. WHEELER. 50
